UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

CORRUGATED METALLIC ELEMENT.

Application filed October 19, 1922. Serial No. 595,632.

My invention relates to the construction of railway cars, and more particularly, to metallic plates or panels formed with integral reinforcing, stiffening and bracing corrugations or embossments which may be incorporated in the construction of car end walls, side walls, floors, roofs or doors used in connection with railway cars of the various types.

10 One of the objects of my invention is to provide a corrugated metallic plate structure for railway cars in which the corrugations have a configuration and arrangement that impart to the plate or structure composed 15 of plates a greater capacity for resisting the mechanical forces tending to destroy them, and by the same means keep the weight reduced to a minimum.

Another object is to form a metallic plate 20 with integral corrugations or ribs which impart to it a certain amount of strength and rigidity adjacent the edges of the plate to resist loads imposed thereon and to provide other integral corrugations or ribs 25 within such corrugations adjacent the middle thereof to provide a certain amount of resiliency adjacent the middle of the corrugation to enable the plate to deflect and return to its normal position without appreciable amount of permanent distortion.

30 Another object is to obtain the desired strength, rigidity and resiliency by a particular and peculiar relative position and relation of a plurality of corrugations.

35 A further object is to provide a corrugated metallic plate of great strength and resiliency at the center.

A further object is to provide a corrugated metallic plate that is stiff diagonally.

40 In the drawings:

Fig. 1 is a front view of a corrugated plate.

Fig. 2 is a top view of Fig. 1.

Fig. 3 is a cross section of Fig. 1 on line 45 3—3.

Fig. 4 is a cross section of Fig. 1 on line 4—4.

Fig. 5 is a cross section of Fig. 1 on line 5—5.

50 Fig. 6 is a front view of a corrugated plate of modified form.

Fig. 7 is a top view of Fig. 6.

Fig. 8 is a cross section of Fig. 6 on line 8—8.

Fig. 9 is a cross section of Fig. 6 on line 9—9.

Fig. 10 is a cross section of Fig. 6 on line 10—10.

Fig. 11 is a front view of a corrugated plate of modified form.

Fig. 12 is a top view of Fig. 11.

Fig. 13 is a cross section of Fig. 11 on line 13—13.

Fig. 14 is a cross section of Fig. 11 on line 14—14.

Fig. 15 is a cross section of Fig. 11 on line 15—15.

Like characters of reference designate like parts.

Referring to Figs. 1 to 5 inclusive, numeral 1, is the plate, 2 the plane of the plate. Numeral 5 is the major corrugation that forms the principal stiffening and rigidifying element; 6 is the valley formed between the major corrugations 5; 7 is the minor corrugation that is formed within the major corrugation 5; 8 is the extremity of the corrugation and 9 is the flat apex of the major corrugation.

The major corrugations 5 are uniform in width and parallel to one another and are provided with minor corrugations 7 that taper in width and depth from the apices 9 and extremities 8 toward the center of the major corrugations 5 forming in effect with the valleys 6 a plurality of contiguous and sinuous corrugations at the center of the plate that are uniform in width and depth, as at section 3—3.

Fig. 2 is a top view of Fig. 1 and shows the major corrugation 5 and the minor corrugation 7 tapering in depth from the apices 9 and extremities 8 toward the center of the major corrugations 5.

Fig. 3 is a cross section showing the uniform contiguous and sinuous formation and the convergence of the major and minor corrugations and the valleys 6 adjacent the center of the plate.

Fig. 4 is a cross section showing the minor corrugations 7 pressed in an opposite direction within the major corrugations 5 mid-

way between the center of the plate and the extremities of the corrugations.

Fig. 5 is a cross section showing the relatively wide major corrugation 5 provided with flat apices 9 and the valleys 6 just before merging into the original plane 2 of the plate 1.

Figs. 6 to 10 inclusive show a modification of the corrugated plate shown in Figs. 1 to 10 5 inclusive in which 10 is the plate, 11 is the plane of the plate, 12 is the major corrugation, 13 is the minor corrugation and 14 is the valley.

The major corrugations 12 are of uniform 15 depth but of varying width being widest adjacent the center and are provided with minor corrugations 13 that taper in width and depth from the apices 15 and the extremities 16 toward the center of the major 20 corrugations 12 forming in effect a plurality of contiguous and sinuous corrugations adjacent the center of the plate that are uniform in width and depth, as at section 8—8. The valleys 14 being narrowest adjacent the 25 center of the plate widen toward the extremities 16 of the corrugations.

Fig. 7 is a top edge view of Fig. 6 and shows the major corrugation 12 of uniform depth and the minor corrugation 13 tapering in depth from the apices 15 and extremities 16 of the major corrugation toward the center.

Fig. 8 is a cross section and shows the contiguous and sinuous formation and the convergence of the major and minor corrugations and the valleys 14 adjacent the center of the plate.

Fig. 9 is a cross section and shows the minor corrugations 13 pressed in an opposite direction within the major corrugation 12 midway between the center of the plate and the extremities 16 of the corrugations.

Fig. 10 is a cross section and shows the major corrugations 12 of uniform depth and width provided with flat apices 15 just before merging into the original plane 11 of the plate 10 and with the parts of the plate between the major corrugations also flat.

Figs. 11 to 15 inclusive show a modification of the corrugated plate shown in Figs. 6 to 10 inclusive and is similar in all respects except that the major corrugations 17 are provided with two minor corrugations 18.

The preferred form comprises a plurality of corrugations or embossments spaced apart distances substantially equal to their width adjacent the middle of the plate that merge into each other to form a lesser number of 86 corrugations adjacent the edges of the plate also spaced apart distances equal to their width and the middle and end portions of the corrugations are symmetrical in cross section about a line midway between the outermost portions of the corrugations so that

this line is the neutral axis of the cross section, thus producing a very strong section for the amount of material used.

Metallic plates corrugated as described wherein a plurality of corrugations merge into a contiguous, sinuous and uniform configuration at the center possess the advantage of great strength and elasticity and (by merging the corrugations together at their extremities) simplifies the termination into the original plane and margins of the plate resulting in a plate of comparatively little weight of maximum strength and one that is easy to manufacture. Although the figures disclose a plurality of sinuous corrugations merging together at the center, it is to be understood that my invention is not limited to this particular configuration but the corrugations at this point may be of any cross section.

This application is confined to the construction wherein the major corrugation is split into two or more minor corrugations, while my application Serial No. 595,634, filed October 19, 1922, on metal end structures for railway cars covers the construction wherein the minor corrugations merge to form the major corrugation. My co-pending applications Serial No. 132,622 and No. 132,623, both filed August 30, 1926, specifically cover the structure as applied to wall elements for railway cars.

The accompanying drawings illustrate the preferred form of the invention, though it is to be understood that the invention is not limited to the exact details of construction shown and described, as it is obvious that various modifications thereof within the scope of the claims will occur to persons skilled in the art.

What I claim is:

1. A metallic plate wall element having a plurality of major and minor corrugations of varying cross section the greater portion of their length, terminating within said plate, and merging together adjacent the center of said plate in a greater number of contiguous corrugations of uniform depth and width.

2. A metallic plate wall element having a plurality of major and minor corrugations terminating within the plate, said major corrugations being parallel, said minor corrugations positioned within said major corrugations being deepest and widest at the center thereof, forming a greater number of corrugations contiguous and of uniform width and depth at the center of said plate.

3. A metallic plate wall element having a plurality of major and minor corrugations terminating within the plate, said major corrugations being widest at the center, said minor corrugations positioned within said major corrugations being deepest and widest at the center thereof, forming a greater num- 130

ber of corrugations contiguous and of uniform width and depth at the center of said plate.

4. A metallic plate having a reinforcement formed therein, comprising a plurality of stiffening ribs which merge into each other to form a relatively wider stiffening rib adjacent the ends of said reinforcement.

5. A metallic plate having a reinforcement formed therein, comprising a plurality of stiffening ribs which merge into each other to form a relatively wider stiffening rib adjacent the ends of said reinforcement, the height of said reinforcement remaining 15 constant the major portion of its length.

6. A metallic panel for a railway car structure having a plurality of reinforcements formed therein with their longitudinal axes substantially parallel, the middles 20 of said reinforcements and the parts of the panel between them comprising tension and compression members substantially equal in width connected by webs spaced substantially equi-distant apart, a plurality of said reinforcements merging into each other adjacent their ends so that said reinforcements and the parts of the panel between them comprise relatively wider tension and compression members substantially equal in 25 width connected by webs spaced substantially equi-distant apart.

7. A metallic panel for a railway car structure having a plurality of reinforcements formed therein with their longitudinal axes substantially parallel, the middles 30 of said reinforcements and the parts of the panel between them comprising tension and compression members substantially equal in width connected by webs spaced substantially equi-distant apart, a plurality of said reinforcements merging into each other adjacent their ends so that said reinforcements and the parts of the panel between them comprise relatively wider tension and compression members substantially equal in 35 width connected by webs spaced substantially equi-distant apart, the height of said reinforcements remaining constant the major portion of their length.

50 8. A metallic plate having a plurality of reinforcements formed therein whose longitudinal axes are parallel comprising compression and tension members connected by webs and having reinforcing ribs springing 55 from said tension members adjacent their ends which increase in depth and width toward the center of said reinforcements.

9. A metallic plate having a plurality of reinforcements formed therein whose longitudinal axes are parallel comprising compression and tension members connected by webs and having reinforcing ribs springing 60 from one of said members adjacent their ends, which increase in depth and width toward the center of said reinforcements.

10. A metallic plate provided with a plurality of corrugations terminating adjacent the edge thereof that diverge into a greater number of corrugations at the center of said plate.

70 11. A metal plate provided with a plurality of major and minor corrugations, said major corrugations projecting from the original plane of said plate forming a uniform cross section at the ends thereof with flat apices of greater width at the ends and diminishing in width towards the center of said corrugations where said major and minor corrugations merge and become contiguous and of a sinuous formation.

75 12. A metallic plate having a plurality of major and minor stiffening corrugations of varying cross section throughout the greater portion of their length but merging together adjacent the ends of the corrugations forming a cross section uniform in depth, width and shape symmetrical in cross section about a line midway between the outermost portions of the corrugations.

80 13. A metallic plate provided with a plurality of major and minor corrugations uniform and contiguous at their center, adjacent the middle of said plate and merge into a lesser number of major corrugations adjacent its edges, the major corrugations being struck out parallel with the original plane of the plate, the minor corrugations pressed in opposite direction within the major corrugation, and at an angle to the original plane of the plate.

85 14. A metallic plate provided with a plurality of uniform contiguous corrugations at their center adjacent the middle of said plate that merge into each other to form a lesser number of larger corrugations adjacent the edges of said plate.

90 15. A metallic plate provided with a plurality of convergent corrugations that merge into a lesser number of corrugations adjacent the ends of said corrugations.

95 16. A metallic plate having a plurality of corrugations terminating within said plate that merge into each other to form a lesser number of larger corrugations adjacent the edges of said plate, the cross sectional area of said corrugated plate being equal anywhere between the planes where said corrugations begin to terminate into the plane of said plate.

100 17. A metallic plate provided with a plurality of reinforcements comprising a plurality of stiffening ribs symmetrical in cross section about a line midway between the outermost portions of the ribs which merge into each other adjacent the ends of said reinforcements to form a plurality of wider stiffening ribs symmetrical in cross section about a center line midway between the outermost portions of the ribs.

115 18. A metallic plate provided with a plu-

rality of corrugations spaced apart distances substantially equal to their width, said corrugations merging adjacent the ends of the plate into each other to form a lesser member of corrugations spaced apart distances substantially equal to their width.

19. A metallic plate provided with a plurality of corrugations spaced apart distances substantially equal to their width, said corrugations merging adjacent the ends of the plate into a lesser number of wider corrugations spaced apart distances substantially equal to their width.

20. A metallic plate provided with a plurality of corrugations merging adjacent the ends of the plate into a lesser number of wider corrugations.

21. A metallic plate provided with a plurality of sinuous corrugations, said corrugations merging adjacent the ends of the plate into a lesser number of corrugations with substantially flat apices.

22. A metallic plate provided with a plurality of sinuous corrugations, said corrugations merging adjacent the ends of the plate into a lesser number of wider corrugations with substantially flat apices.

23. A metallic plate provided with a plurality of sinuous corrugations with the parts of the plate between said corrugations also of sinuous configuration, said corrugations merging together adjacent their opposite ends to form a plurality of fewer corrugations having substantially flat apices with the parts of the plate between the last mentioned corrugations also being flat.

24. A metallic plate provided with a plurality of sinuous corrugations with the parts of the plate between said corrugations also of sinuous configuration, said corrugations merging together adjacent their opposite ends to form a plurality of fewer wider corrugations having substantially flat apices with the parts of the plate between the last mentioned corrugations also being flat.

25. A metallic plate provided with a plurality of sinuous corrugations with the parts

of the plate between said corrugations also of sinuous configuration, said corrugations merging together adjacent their opposite ends to form a plurality of fewer corrugations having substantially flat apices.

26. A metallic plate provided with a plurality of sinuous corrugations with the parts of the plate between said corrugations also of sinuous configuration, said corrugations merging together adjacent their opposite ends to form a plurality of fewer wider corrugations having substantially flat apices.

27. A metallic panel for a railway car structure having a plurality of reinforcements formed therein with their longitudinal axes substantially parallel, said reinforcements and the parts of the panel between them comprising tension and compression members connected by webs, and reinforcing ribs springing from said tension members adjacent their ends which gradually increase in depth and in width toward the middles of the reinforcements.

28. A metallic panel for a railway car structure having a plurality of reinforcements formed therein with their longitudinal axes substantially parallel, said reinforcements and the parts of the panel between them comprising tension and compression members connected by webs, and reinforcing ribs springing from one of said members adjacent their ends which gradually increase in depth and in width toward the middles of the reinforcements.

29. The metallic panel for a railway car structure having a plurality of reinforcements formed therein with their longitudinal axes substantially parallel, said reinforcements and the parts of the panel between them comprising tension and compression members connected by webs, and reinforcing ribs springing from one of said members adjacent their ends which gradually increase in depth toward the middles of the reinforcements.

ARTHUR E. SMALL.
